FIG. 14

FIGURE 1 is a front perspective view of one embodiment of a snow excluder for a boot top showing my new design, wherein the excluder is formed of two separable interfitting halves of uniform thickness; a shrouded ski boot is shown in broken lines for environmental purposes;

FIGURE 2 is a rear view thereof;

FIGURE 3 is a side elevational view of the snow excluder of FIGURE 1;

FIGURE 4 is a side elevational view of the side opposite that shown in FIGURE 3;

FIGURE 5 is a front elevational view thereof;

FIGURE 6 is a rear elevational view thereof;

FIGURE 7 is a top plan view thereof;

FIGURE 8 is a bottom plan view thereof;

FIGURE 9 is a front perspective view of another embodiment of the snow excluder for a boot top wherein the excluder is formed of a single piece of flexible material of uniform thickness opening only at the front. A laced ski boot is shown in broken lines for environmental purposes;

FIGURE 10 is a rear view thereof;

FIGURE 11 is a side elevational view of the snow excluder of FIGURE 9;

FIGURE 12 is a side elevational view of the side opposite that shown in FIGURE 11;

FIGURE 13 is a front elevational view thereof;

FIGURE 14 is a rear elevational view thereof;

FIGURE 15 is a top plan view thereof; and

FIGURE 16 is a bottom plan view thereof.

We claim:

The ornamental design for a snow excluder for a boot top, as shown and described,
